B. W. STEARNS,
INTERNAL COMBUSTION POWER SYSTEM,
APPLICATION FILED MAR. 12, 1914.

1,188,506.

Patented June 27, 1916.

UNITED STATES PATENT OFFICE.

BENJAMIN W. STEARNS, OF UNADILLA, NEW YORK.

INTERNAL-COMBUSTION POWER SYSTEM.

1,188,506.

Specification of Letters Patent. Patented June 27, 1916.

Application filed March 12, 1914. Serial No. 824,260.

To all whom it may concern:

Be it known that I, BENJAMIN W. STEARNS, a citizen of the United States, residing at Unadilla, in the county of Otsego and State 5 of New York, have invented certain new and useful Improvements in Internal-Combustion Power Systems, of which the following is a specification, reference being had therein to the accompanying drawing.

10 The invention relates to internal combustion engines provided with auxiliary devices for utilizing and transforming into power the surplus heat which, according to common practice, is usually dissipated in the cooling 15 system and in the exhaust. By my invention I provide supplemental cylinders having pistons connected with the main crank shaft, an auxiliary pump for compressing air, and means whereby the compressed air from the 20 pump can be highly heated by the explosion cylinders and exhaust gases and expanded, after which it is admitted to the auxiliary cylinders to drive the pistons therein.

The principal object therefore of my invention is to provide an internal combustion 25 engine having auxiliary mechanism of the sort above referred to.

Further objects of the invention are to provide numerous improved features adapted 30 to coöperate with the above mentioned devices to increase the efficiency of the engine and to provide for its convenient operation.

In the accompanying drawings I have for the sake of illustration shown one form of 35 mechanism embodying the invention, but as many of the parts can be of any of the standard well known types these parts have there been shown conventionally and in some cases omitted entirely. The drawings are intended 40 merely to guide the engineer in the construction of an engine embodying my invention, and as to the various details of construction, the proportion and arrangement of parts, etc., there can be wide variation.

45 Referring to the drawings, Figure 1 is a vertical sectional view taken through the longitudinal center of the engine, some of the parts being shown in elevation. Fig. 2 is a horizontal sectional view taken along the line 2—2 of Fig. 1. Fig. 3 is a fragmentary sectional view taken along the line 3—3 of Fig. 2. Fig. 4 is a view similar to Fig. 3

taken along the line 4—4 of Fig. 2. Fig. 5 is a fragmentary sectional view taken along the line 5—5 of Fig. 3. Fig. 6 is a sectional view taken along the line 6—6 of Fig. 2. Fig. 7 is a fragmentary sectional view taken along the line 7—7 of Fig. 1.

Referring to the drawings, 1 and 2 represent respectively the lower and upper halves of the main crank case which is provided with main crank shaft bearings at 3, 4 and 5. Mounted in these bearings is the crank 6 having, in the construction shown, four crank arms with bearings for four connecting rods. At one end of the crank shaft is a suitable fly-wheel 6a. Mounted upon the upper half of the crank case 2 are the cylinders 7 and 8 which can be formed in any usual or preferred way, but which are shown as comprising a single body casting 9 and a single head casting 10. Slidable in the cylinders 7 and 8 are pistons 11 and 12 connected respectively with the crank shaft 6 by the connecting rods 13 and 14. In Figs. 3 and 4 are shown valve mechanisms for controlling the admission and exhaust of gases to and from the cylinders 7 and 8; but as to these valve mechanisms there can be wide variation, they of themselves forming no part of my invention. As shown the explosive gases are admitted from the manifold 15 through the valve 16 to the explosion space above the piston when they are fired by the spark plug 17. The exhaust gases pass out through the valve 18 into the exhaust passage 19 which will be further referred to.

I have shown in the drawings and have described an internal combustion engine of the two cylinder four-cycle type, but it will be understood that an engine of this type is not essential and that so far as my invention is concerned engines of other types may be used.

The crank shaft 6 is provided at one end (preferably the forward end when the engine is used in an automobile or similar vehicle) with a supplemental crank arm 20 having a pin which works in a slotted transversely slidable cross head 21.

22 and 23 are two oppositely positioned low pressure cylinders in which are located respectively pistons 24 and 25 suitably connected to the cross head 21.

26 and 27 are high pressure cylinders preferably connecting rigidly, respectively, to the low pressure cylinders 22 and 23. In these cylinders are pistons 28 and 29, preferably connected rigidly, respectively, to the pistons 24 and 25.

30 is an intermediate receiver positioned above the several cylinders.

In operation when the crank shaft 6 is 10 turned the cross head 21 is reciprocated and with it the pistons 24, 25, 28 and 29. Atmospheric air is drawn into the cylinders 22 and 23 through the valved ports 31 and 32 and discharged at increased pressure into the receiver 30 through the valved ports 33 and 34. Air from the receiver 30 passes into the cylinders 26 and 27 through the valved ports 34 and 35 and from the cylinders is forced under still further increased pressure into the 20 pipes 36 and 37. The pipes 36 and 37 communicate with the air passages 38 formed around the cylinders 7 and 8 and from these passages the air is discharged into the receiver 39 above the cylinders.

25 The air is drawn into the compressing apparatus above described at atmospheric temperature and even after compression is relatively cool and therefore quite dense, as compared with its subsequent condition. 30 However, immediately upon entering the passages 38 surrounding the explosion cylinders the air becomes greatly heated and at once expands and becomes at once relatively rarefied. This heated rarefied air 35 rises into the receiver 39 where it is available for use in the manner to be described.

Mounted upon the upper half 2 of the crank case are two supplemental cylinders 40 and 41 which also if desired may be cast 40 in one piece. They are provided respectively with pistons 42 and 43 and with connecting rods 44 and 45 which engage the main crank shaft 6. Above the cylinders 40 and 41 is a receiver 46 which communicates with the receiver 39 through the valved port 47. The exhaust pipe 19 extends first into the receiver 39 and from it into the receiver 46 where it is coiled as indicated at 48. The heated air passes from 45 the receiver 39 into the receiver 46 where it is still further heated and rarefied by contact with the coil 48. Mounted within the receiver 46 is an air tight hood 49, communication between the receiver 46 and the 50 interior of the hood being controlled by means of the valve 50. This valve is provided with suitable connections including the rod 51 by means of which it can be controlled by an operator at a suitable point, 55 as for instance at the dash-board of an automobile. Inside of the hood 49 is a slide valve mechanism 52 connected with the crank shaft by means of suitable gearing 53 to be reciprocated at every revolution of

the shaft. When the valve mechanism is 65 in the position shown in Fig. 1, air from the hood 49 will be admitted to the cylinder 40 through a suitable port 54 to drive the piston downward. At the same time air is discharged from the cylinder 41 through the 70 port 55 into the valve chamber and from the valve chamber through the port 56 (shown in Fig. 7) into the exhaust pipe 57 which communicates with the main exhaust pipe 19. When the slide valve mechanism 75 52 is at the other end of its stroke air is admitted to the cylinder 41 and discharged from the cylinder 40. Preferably, though not necessarily, I provide the auxiliary exhaust passages, as indicated at 58 in Fig. 7. 80

From the foregoing description, the operation of the engine will be readily understood. The internal combustion motor comprising the cylinders 7 and 8 is started in the usual manner and generates power in 85 the usual way. By means of power derived from the internal combustion cylinders and transmitted through the crank shaft 6 the air compressing mechanism is driven and 90 relatively cool air under pressure is supplied to the space surrounding the hot combustion cylinders. This air, as above described, becomes heated and passes first into the receiver 39 and then into the receiver 46 when it is still further heated and expanded by contact with the exhaust coil 48. From the receiver 46 the air is admitted to the hood 49 and from the hood by means of the valve mechanism 52 it is admitted to the cylinders 40 and 41 to drive the pistons 100 95 therein and thus supply supplemental power to the shaft 6. It will be understood that the air in passing from the compressor to the valve mechanism at 52 has because 105 of its increase in temperature been expanded several times in volume with the result that for a given pressure there is several times as much power available for driving the pistons 42 and 43 as was required to drive the compressor mechanism. In this 110 way the heat of the explosion cylinders and of the exhaust gases is transformed into power, the cylinders being kept relatively cool by the incoming air from the compressor and the exhaust gases upon discharge being relatively cool because of the 115 discharge of their heat at the coil 48.

Under some circumstances it may be found that the air supplied from the compressor mechanism is not sufficient to properly cool the cylinders 7 and 8. When this is found to be the case, I provide a supplemental cooling chamber 59 in the head 10 above the cylinders. Openings 60 and 61 communicate with the external air and a pipe 62 communicates with the main exhaust pipe 19. The suction of the exhaust draws air through the exhaust pipe 62 and thus causes 120 125

the entry of cold air through the openings 60 and 61. In this way the cylinders 7 and 8 are supplementally cooled.

In some circumstances it may be found 5 desirable to increase the storage capacity for compressed air. When additional storage capacity is found to be desirable I provide a pressure tank 63 which communicates with the receiver 39 by means of a pipe 64 10 and with the receiver 46 by means of a pipe 65. It will be seen that the air from the receiver 39 can be passed to the tank 63, and that even if it becomes cooled in the said tank it will be again heated upon reaching 15 the receiver 46 and coming into contact with the coil 48. When the engine embodying my invention is to be used upon an automobile the tank 63 can conveniently be located underneath the front seat.

20 By closing the valve 50 just prior to the stopping of the engine a charge of the compressed air can be retained in the receivers 39 and 46 (and in the tank 63 if used). After the engine has been stopped and it is 25 desired to start it again, starting can be accomplished by opening the valve 50 which will at once admit air to drive the pistons 42 and 43 which will in turn drive the pistons 11 and 12. In this way the internal 30 combustion engine is started and there is no need for the usual hand-crank or automatic "self-starter."

What I claim is:

1. The combination of an internal combustion engine having cylinders provided 35 with jackets open at their upper ends, an air compressor driven by the engine, an air motor, a duct leading air from the compressor to the cylinder jackets of the engine 40 where it is heated and expanded, and a receiver for the heated and expanded air from the jackets, the said receiver being immediately above the cylinders in direct communication with the open ends of the jackets 45 and having valve controlled communication with the air motor whereby the heated and expanded air can be utilized for the development of power.

2. The combination of an internal combustion engine having jacketed cylinders, 50 an air compressor driven by the engine, an air motor having its power transmitting parts mechanically connected with the power transmitting parts of the internal 55 combustion engine, a duct leading air from the compressor to the cylinder jackets of the engine where it is heated and expanded, a receiver for the heated and expanded air from the jackets, the said receiver having 60 valve controlled communication with the air motor whereby the heated and expanded air can be utilized for the development of power, and an exhaust pipe extending from the engine through the receiver and serving

to maintain the air therein in a heated and 65 expanded condition.

3. The combination of an internal combustion engine having jacketed cylinders, an air compressor driven by the engine, an air motor having its power transmitting parts mechanically connected with the power transmitting parts of the internal combustion engine, a duct leading air from the compressor to the cylinder jackets of the engine where it is heated and expanded, 70 a receiver for the heated and expanded air from the jackets, a second receiver having check valve controlled communication with the first receiver, the said second receiver having valve controlled communication 75 with the air motor whereby the heated and expanded air can be utilized for the development of power, and an exhaust pipe extending from the engine through both of the receivers and serving to maintain the air therein in a heated and expanded condition.

4. The combination of an internal combustion engine having jacketed cylinders, an air compressor driven by the engine, an air motor, a duct leading air from the compressor to the cylinder jackets of the engine where it is heated and expanded, a receiver for the heated and expanded air from the jackets, a pressure tank separated from 90 the receiver, the said receiver having valve controlled communication with the air motor whereby the heated and expanded air can be utilized for the development of power, the said valve-controlled communication 95 being entirely independent of the said pressure tank, and a pipe connecting the tank and receiver.

5. The combination of an internal combustion engine having jacketed cylinders, 100 an air compressor driven by the engine, an air motor, a duct leading air from the compressor to the cylinder jackets of the engine where it is heated and expanded, a receiver for the heated and expanded air from the jackets, a second receiver having check 105 valve controlled communication with the first receiver, the said receiver having valve controlled communication with the air motor whereby the heated and expanded air can be utilized for the development of power, a pressure tank separated from the receivers, a pipe connecting the first receiver with the tank, and a second pipe connecting the tank with the second receiver.

6. The combination of an internal combustion engine having cylinders provided with jackets open at their upper ends and with supplemental cooling chambers extending horizontally across their tops, an air compressor driven by the engine, an air motor, a duct leading air from the compressor to the cylinder jackets of the engine 125

where it is heated and expanded, a receiver above and immediately adjacent the tops of the cylinder and the supplemental cooling chambers therein, the said receiver communicating directly with the open ends of the jackets, means for conducting the heated and expanded air from the receiver to the air motor where it is utilized for the development of power, and means for causing at-

mospheric air to move through the cooling 10 chambers of the cylinders.

In testimony whereof, I affix my signature, in presence of two witnesses.

BENJAMIN W. STEARNS.
